TROWEL

Filed Sept. 28, 1926

FIG. 1.

FIG. 2.

FIG. 3.

Inventor
W.C. Pratt.

By *Watson E. Coleman.*

Attorney

UNITED STATES PATENT OFFICE.

WILLIAM C. PRATT, OF JONESBORO, ARKANSAS.

TROWEL.

Application filed September 28, 1926. Serial No. 133,229.

This invention relates to trowels and more particularly to a trowel for use by masons in laying the walls of hollow tile and the like.

5 An important object of the invention is to provide a device of this character so constructed that the trowel may be employed to grasp one end of the tile in the operation of shifting the tile into its position upon 10 the wall, so that the mason need not lay down his trowel at this time.

A further object of the invention is to so construct the grasping mechanism employed upon the trowel that during the operation of 15 picking up mortar from the board and applying this mortar to the face of tiles, it will not be in the way.

20 A further object of the invention is to produce a device of this character which may be readily and cheaply constructed, which 25 will be durable and efficient in service and a general improvement in the art.

These and other objects I attain by the 30 construction shown in the accompanying drawing, wherein for the purpose of illustration is shown a preferred embodiment of my invention and wherein:—

Figure 1 is a side elevation showing a 35 trowel constructed in accordance with my invention applied to one end of a tile to assist in lifting the same, the gripping element being illustrated in its inoperative position in dotted lines;

Figure 2 is a bottom plan view of the 40 trowel;

Figure 3 is a vertical sectional view through the trowel showing the manner of mounting the gripping element therein;

Figure 4 is a fragmentary sectional view 45 showing the manner of connecting the head with the stem.

Referring now more particularly to the drawing, the numeral 10 generally designates the blade of a trowel and 11 a shank secured thereto and having an offset tang 50 12 for engagement with the handle 13. The connecting bar 14 providing the offset in the shank is thickened at a point adjacent the end of the handle, as at 15, and has formed therethrough a bore 16, the upper end of 55 which is enlarged, as at 17. Adjacent its lower end, the connecting bar 14 is provided upon its rear face with a boss 18 which is provided with an opening 19 co-axial with

the bore 16. The opening 19 is preferably 55 polygonal in shape, for a purpose presently to appear.

Slidably directed through the opening 19 is a stem 20, the lower end of which has a foot 21 underlying the adjacent end of the 60 trowel blade 10. The upper end of this stem has a reduced extension 22 fitting the bore 16 and projecting upwardly into the enlarged portion 17 thereof. Within this enlarged portion a head 23 is secured to the extension, which head fits the enlarged portion 17 of the bore and projects above the upper surface of the handle, so that it may be readily engaged by the thumb of the operator. Between the bottom of the enlarged 65 portion of the bore and the head, a spring 24 is disposed, which normally urges this head upwardly. The bottom of the blade 10 at the rear end thereof is preferably provided with a recess 25 in which the head 21 70 75 engages when moved upwardly under the influence of the spring 24.

In the use of the device, when it is desired 80 to lift the tile to the wall, the operator depresses the foot 21 by engaging the head 23 with his thumb until there is sufficient space between the upper surface of the foot 21 and the adjacent face of the blade to permit the tile to be slipped therebetween. The trowel is then properly placed upon the tile 85 and the thumb released from the head 23, permitting the foot 21 to move upwardly under the influence of the spring 24 and clamp the end of the tile. The other hand 90 of the operator is then engaged with the opposite end of the tile and the tile lifted into position. In withdrawing the trowel, it may be directly slipped from the tile or the head 23 may be depressed to permit release of the tile. Under ordinary circum-

stances, as when applying mortar to the 95 face of the tiles or removing mortar from the boards, the spring 24 will maintain the foot 21 housed within the recess 25, so that it does not interfere with the operation of the trowel and the trowel acts in the usual manner. It is pointed out that by this structure, the weight of the trowel-engaged end of the tile is placed very close to the hand and not spaced from the hand as it 100 would be where the operator followed the usual practice and engaged the point of his trowel in the opening of the tile. The con-

nnection between the head 23 and shank 22 is preferably threaded, as shown more clearly in Figure 4, so that this head may be adjusted to regulate the distance between the upper 5 face of the foot 21 and the lower face of the blade 10 when the foot is depressed.

Since it is obvious that the construction hereinbefore set forth is capable of a certain range of change and modification without 10 materially departing from the spirit of the invention, I do not limit myself to such specific structure except as hereinafter claimed.

I claim:—

- 15 1. In a trowel, a blade, a handle connected to the blade at one end thereof, a member having a foot opposing the bottom of the blade at said end, a spring normally maintaining the foot in engagement with the blade and means engageable by a member of a hand engaging the handle for shifting said member against the action of the spring to separate the foot from the bottom of the blade.
- 20 2. In a trowel, a blade, a handle connected to the blade at one end thereof, a member having a foot opposing the bottom of the blade at said end, a spring normally maintaining the foot in engagement with the blade and means engageable by a member of a hand engaging the handle for shifting said member against the action of the spring to separate the foot from the bottom of the blade, said blade having a recess receiving the underlying portion of the foot whereby the bottoms of the foot and blade

are substantially co-planar when the foot is in engagement with the blade.

3. In a trowel, a blade, a handle connected with the blade at one end thereof and means at said end of the blade for co-acting with the blade to clampingly engage the wall of tile or the like, the blade having a recess within which the opposed portion of said means is normally housed. 45

4. In a trowel, a blade, a shank connected with the blade and having an offset tang adapted for connection with a handle, the offset portion of the blade providing a mounting for a member having a foot underlying the blade and a spring normally urging said member upwardly to thereby maintain the foot in engagement with the blade or with an article disposed between it and the blade. 55

5. In a trowel, a blade, a shank connected with the blade and having an offset tang adapted for connection with a handle, the offset portion of the blade providing a mounting for a member having a foot underlying the blade and a spring normally urging said member upwardly to thereby maintain the foot in engagement with the blade or with an article disposed between it and the blade, the upper end of said member being arranged adjacent said tang to thereby permit engagement of the member by a finger of a hand engaging the handle of the trowel. 60

In testimony whereof I hereunto affix my 70
signature.

WILLIAM C. PRATT.
